UNITED STATES PATENT OFFICE.

NATHANIEL T. WORTHLEY, OF BRUNSWICK, MAINE.

WASHING-MACHINE.

SPECIFICATION forming part of Letters Patent No. 783,917, dated February 28, 1905.

Application filed September 22, 1903. Serial No. 174,194.

To all whom it may concern.

Be it known that I, NATHANIEL T. WORTHLEY, a citizen of the United States, and a resident of Brunswick, in the county of Cumberland and State of Maine, have made a certain new and useful Invention in Washing-Machines; and I declare the following to be a full, clear, and exact description of the same, such as will enable others skilled in the art to which it appertains to make and use the invention, reference being had to the accompanying drawings, and to letters of reference marked thereon, which form a part of this specification.

15 Figure 1 is a section on the line 1 1, Fig. 2. Fig. 2 is a central longitudinal section of the washing-machine on the line 2 2, Fig. 1.

The invention has relation to washing-machines, and has for its object the improvement 20 of my washing-machine patented May 21, 1872, and numbered 127,133, with the object of enabling light fabrics which have a tendency to wind around the small lower rolls to be untangled therefrom with facility.

25 With this object in view the invention consists in the novel construction and combinations of parts, all as hereinafter described, and pointed out in the appended claim.

In the accompanying drawings, illustrating 30 the invention, the letter *a* designates the base of the main frame, to which are secured the uprights *b* at the ends thereof, these uprights being provided each with a vertical slot or way *c*, in which is arranged a spiral spring *d*, providing a yielding bearing for the journal ends *e* of the rocker-frame *f*. In the upper ends of the uprights are pivoted the journals of the large corrugated roller *h*, which is designed to be turned by means of a crank.

40 The rocker-frame consists of the sides *l* and the longitudinal center bar *m*, which is extended beyond the sides to form the journal ends *e*. The sides *l* are extended upward and outward to form the handle-guards *p* and are 45 provided with the bearings *q*, open at their upper ends. In the bearings *q*, which are ar-

ranged at the sides of the central bar *m*, are located the journals of the under rollers *s*, there being two of these under rollers laterally arranged below the large roller *h* and designed 50 to operate in connection therewith. The handle-guards *p* extend upward and outward in somewhat parallel relation to the circumferential contour of the large roller in such wise as to guide the goods in their passage between 55 the large roller and the under rollers, so that they will move freely when being drawn upward by the operation of the large roller. These handle-guards serve also to provide accessible handles for depressing the rocker-frame when it becomes necessary to remove 60 an under roller from its bearing to disengage light articles, such as fringes, &c., which may become wound around the roller. The handle-guards also serve as bearings to receive the 65 roller-journals when displaced from the bearings *q* temporarily for the purpose above indicated, a bearing-recess *p'* being provided in these handle-guards intermediate of the journal-bearings *q* and the outer ends of the handle-guards for the reception of the roller-journals which will rest therein. As the handle-guard of one side assumes a horizontal or 70 nearly horizontal position when the rocker-frame is depressed on one side the roller of 75 that side can be easily slipped out of the bearings *q* upon the guards *p*, which support it while the adjustment of the goods is being accomplished. In its operation the clothes are worked back and forth between the upper large roller and the under rollers, the construction allowing the latter to accommodate 80 themselves to the bulk of the articles being washed.

Having described this invention, what I 85 claim, and desire to secure by Letters Patent, is—

In a washing-machine, the combination with the vertically-slotted uprights of the main frame, the spring and the large corrugated 90 roller journaled therein, of the yielding pivoted rocker-frame having the journal-bear-

ings open at the top, the upward and outward inclined handle-guards having a bearing-recess intermediate of said journal-bearings and the outer ends of said handle-guards, and re-
5 movable laterally-arranged lower rollers having journals removably seated in the open top bearings of the rocker-frame, and adapted to be received and to rest in the bearing-re-

cesses of the handle-guards, substantially as specified.

In testimony whereof I affix my signature in presence of two witnesses.

NATHANIEL T. WORTHLEY.
